DESIGN FOR A STORE BACK FIXTURE

Morris Ketchum, Jr., Francis X. Gina, and John S. Sharp, New York, N. Y., assignors to Ketchum, Gina & Sharp, New York, N. Y., a co-partnership

Application June 25, 1947, Serial No. 139,915

Term of patent 14 years

(Cl. D80—11)

To all whom it may concern:

Be it known that we, Morris Ketchum, Jr., Francis X. Gina, and John S. Sharp, citizens of the United States and residents of New York city, in the county and State of New York, have invented a new, original, and ornamental Design for a Store Back Fixture, of which the following is a specification, reference being had to the accompanying drawings, forming a part thereof.

Fig. 1 is a perspective view showing the front and one end of the store back fixture; and

Fig. 2 is a section on the line 2—2 of Fig. 1.

We claim:

The ornamental design for a store back fixture, substantially as shown.
